UNITED STATES PATENT OFFICE

CHARLES DOMM, OF DETROIT, MICHIGAN, ASSIGNOR OF ONE-FOURTH TO LOUIS J. GILCHRIST, OF DETROIT, MICHIGAN

CONTAINER FOR USE WITH REFRIGERATORS AND DISPLAY COUNTERS

Application filed November 15, 1930. Serial No. 495,979.

This invention relates to containers for use with refrigerators, meat display counters and the like, the general object of the invention being to provide a chamber forming member 5 for receiving articles to be placed in the refrigerator or meat display compartment to save moisture and minimize the drying of the articles, as they do when placed in electric refrigerators.

10 Another object of the invention is to provide means whereby air can be caused to circulate through the container from the interior part of the refrigerator or display compartment and also to make the container transparent in part so that articles placed therein can be seen, especially when the invention is used with the display compartments of meat counters and the like.

15 This invention also consists in certain other features of construction and in the combination and arrangement of the several parts, to be hereinafter fully described, illustrated in the accompanying drawing and specifically pointed out in the appended claim.

20 In describing the invention in detail, reference will be had to the accompanying drawing wherein like characters denote like or corresponding parts throughout the several views, and in which:—

25 Figure 1 is a sectional view through the display compartment of a counter, showing the invention in use.

Figure 2 is a view of the cover of the device.

30 Figure 3 is a similar view, but showing the dampers in closed position.

Figure 4 is a section on line 4—4 of Figure 1.

35 In this drawing, the numeral 1 indicates the display compartment of a counter for displaying meat or other articles while the articles are subjected to chilled air which is circulated through the compartment in the known manner. It is well known that meat and some other articles placed in such compartments will soon deteriorate, due to the moisture therein being removed by the circulating air, and in order to prevent this drying action, I provide a casing A to receive the articles. This casing is placed in the

display compartment and in order that the articles therein can be seen, I form the walls of the casing of transparent material, as shown. Thus one looking into the display compartment can see the articles in the casing. 55

The bottom 1a of the casing is preferably made of porcelain and may be made removable. It is spaced from the lower end of the casing so that air can pass from the compartment through the openings 2 into 60 the casing. A screen 3 is held slightly above the bottom 1a by the supports 4 and the articles are placed on this screen.

65 The front top part of the casing slopes downwardly as shown, and has a large opening therein for the placing of articles in the casing and their removal therefrom. A removable lid 5 covers this opening and is provided with a handle 6. This lid has a number of openings 7 therein which are controlled 70 by the dampers 8 attached to a rod 9 which is slidably connected with the lid by the brackets 10. A handle 11 is formed on the rod so that it can be moved to cause the dampers to close the openings or to uncover 75 or partly uncover the same. Thus the amount of air passing through the casing can be regulated or entirely stopped.

80 The top part 12 of the casing can be used to display meat and other articles when desired. Of course, the articles should not be allowed to remain on this top part very long or else they will dry out.

85 The device can be also placed in home refrigerators to prevent articles placed therein from drying out, and it will be understood that as many of the devices can be used as is necessary or desired.

90 It is thought from the foregoing description that the advantages and novel features of the invention will be readily apparent.

95 It is to be understood that changes may be made in the construction and in the combination and arrangement of the several parts, provided that such changes fall within the scope of the appended claim.

What I claim is:—

100 A container of the character described comprising a casing having a forwardly inclined upper front portion with an opening

therein, a lid removably fitted in the opening and having a row of spaced substantially elongated apertures, guide eyes mounted externally on the lid in spaced alignment with each other at one side of the apertures, a bar 5 slidably and swingingly fitted in the eyes and having right angular spaced extensions, and bumpers on the extensions and engageable over and from the apertures on manual manipulation of the bar for the closing and 10 opening of said apertures.

In testimony whereof I affix my signature.
CHARLES DOMM.
